UNITED STATES PATENT OFFICE.

MARK E. FERNALD, OF SOUTHBORO, MASSACHUSETTS.

WELTING.

Application filed June 9, 1923. Serial No. 644,303.

To all whom it may concern:

Be it known that I, MARK E. FERNALD, a citizen of the United States, residing at Southboro, in the county of Worcester and State of Massachusetts, have invented certain Improvements in Welting, of which the following description, in connection with the accompanying drawings, is a specification, like reference characters on the drawings indicating like parts in the several figures.

The present invention relates to an improved welting for use in the manufacture of welt shoes.

15 Welting used in the manufacture of welt shoes is generally sold to the shoe manufacturers in a skein made up of a number of separate pieces joined together to form a continuous strip. The separate pieces are joined by oppositely scarfing the ends of the pieces, superimposing the scarfed ends and securing them together by cement under pressure. With this construction, the lap of the joint appears on both edge faces of the 20 strip along a long slanting line which extends from the bottom to the top of the strip. This joint presents a difficulty to manufacturers of Blake welt shoes in which the inseam for uniting the welt to the shoe upper and insole passes through a shoulder in the welt formed by longitudinally slitting one 25 edge face thereof. Some of the tools which form the Blake inseam operate in the slit of the welt and consequently operate in a 30 plane closely approaching the plane of the lap on the welt. These tools separate the lap and thus open up the joint in the welt and therefore care has been exercised heretofore in sewing Blake welt shoes to prevent 35 a joint appearing in the length of the welt strip required for a shoe. This is wasteful and negatives to some extent the large saving in welting due to the fact that welting for Blake welt shoes is not as wide as 40 for Goodyear welt shoes.

The object of the present invention is to provide an improved welting which is well suited for the manufacture of Blake welt shoes and which will overcome the disadvantages hereinbefore referred to.

45 In accordance with this object the features of the present invention consist in a welting having certain novel features herein-after described and claimed, the advantages of which will be readily understood by those skilled in the art.

The various features of the present invention will be best understood from an inspection of the accompanying drawings illustrating the preferred embodiment of the invention, in which

Figure 1 is an elevation of one of the pieces to be joined;

Fig. 2 is an elevation of the other piece;

Fig. 3 is a plan (third angle projection) 65 of the piece shown in Figure 1;

Fig. 4 is a plan of the piece shown in Fig. 2;

Fig. 5 is a plan of the joint;

Fig. 6 is an end elevation of the welting 70 showing the longitudinal slit formed in one edge face; and

Fig. 7 is a plan of the joint indicating the course of the inseam along the shoulder formed by the longitudinal slit. 75

The two separate pieces which are to be joined to form a strip of welting are shown at 8 and 9 (Figs. 1 and 2). The piece 8 is scarfed from the point 10 (which is called the line of the scarf) to the end of the piece 80 where it terminates in a feather edge. At the line of the scarf 10 the scarf is not as wide as the strip, but gradually increases in width until at the end of the piece the scarf extends the full width of the strip. This 85 construction provides a wall 11 extending only part way across the strip which at the end of the piece has a feather edge but which gradually increases in width until it meets the line of the scarf 10. As the wall 11 increases in width it decreases in height until it merges with the uncut portion of the strip 90 8 at the line of scarf 10.

The other piece 9 is provided with a scarf 12 opposite in direction to the scarf on the 95 piece 8. The width of the scarfed portion of the piece 9 is gradually reduced from the line of scarf 13 to the end of the piece in order that when the pieces 8 and 9 are superimposed the edge face 14 on the piece 100 9 will extend along the wall 11 (Fig. 5).

After the pieces are superimposed and secured together by cement one edge face of the strip of welting is provided with a longitudinal slit 15 (Figs. 5, 6 and 7). By 105 means of this slit a shoulder 16 is formed at the base thereof and it is this shoulder that holds the inseam stitches 17 (Fig. 7) of a Blake welt shoe.

With this joint the diagonal lap, which 110 appears on the slit face, terminates at the wall 11 so that there is no diagonal lap on

the unslit edge face of the welt. The wall 11 provides a substantial piece of stock to effectively resist the tendency of the inseamming tools to open up the joint during their 5 thrust therethrough. The unslit edge face of the welting has a vertical lap at the point 18 (Fig. 5) but at this point the full uncut portion of the piece 9 is positioned so that the vertical lap 18 does not weaken the joint.

10. What is claimed as new, is:

1. As an article of manufacture a strip of welting for use in the manufacture of shoes having a shoulder formed by longitudinally slitting one edge face of the strip

15 and having a joint therein comprising two separate pieces oppositely scarfed, superimposed, and secured together, one of which is provided with a wall extending between the shoulder and the unslit edge face of the strip

20 from one end of the joint to the other end.

2. As an article of manufacture a strip of welting for use in the manufacture of shoes having a joint therein comprising two separate pieces oppositely scarfed, superim-

25 posed, and secured together, the scarf on one piece extending across the width of the strip only at the line of the scarf and the scarf on the other piece extending across the width of the strip only at the end of the

30 scarf.

3. As an article of manufacture a strip of welting for use in the manufacture of shoes having a joint therein comprising two separate pieces oppositely scarfed, superim-

35 posed, and secured together, one edge face of the strip at the joint having a diagonal lap and the other edge face a vertical lap.

4. As an article of manufacture a strip of welting for use in the manufacture of 40 shoes having a joint therein comprising two separate pieces oppositely scarfed, superimposed, and secured together, the diagonal lap showing on only one edge face of the strip.

45 5. As an article of manufacture a strip of welting for use in the manufacture of shoes having a joint therein comprising two separate pieces oppositely scarfed, superim-

posed, and secured together, one of which is provided with a vertical wall arranged to 50 engage an edge face on the other piece, said wall extending only part way across the strip.

6. As an article of manufacture a strip of welting for use in the manufacture of 55 shoes having a joint therein comprising two separate pieces oppositely scarfed, superimposed, and secured together, one of which is provided with a vertical wall extending only part way across the strip, having sub- 60 stantial width at the line of one scarf and a feather edge at the end of the said scarf, arranged to engage an edge face on the other piece throughout the length of the wall.

65 7. As an article of manufacture a strip of welting for use in the manufacture of shoes having a joint therein comprising two separate pieces oppositely scarfed, superimposed, and secured together, one of which is provided with a vertical wall having sub- 70 stantial width at the line thereon and a feather edge at the end of the scarf and having its greatest height at its narrowest portion, and the other one of which is gradually reduced in width from the line thereon to the end of the scarf to form an edge face engaged with the wall throughout its length.

75 8. As an article of manufacture a strip of welting for use in the manufacture of 80 shoes having a joint therein comprising two separate pieces oppositely scarfed, superimposed, and secured together, one of which is scarfed to leave a portion extending only part way across the strip uncut between the

85 line of the scarf and the end of the piece.

9. As an article of manufacture a strip of 90 welting for use in the manufacture of shoes having a joint therein comprising two separate pieces, superimposed and secured together, one of which is cut to leave a diagonal wall extending only part way across the strip along one edge face of the piece.

In testimony whereof I have signed my name to this specification.

MARK E. FERNALD.
